Primary Examiner — Darlington Ly(74) *Attorney, Agent, or Firm* — Andrew F. Young, Esq.; Lackenbach Siegel LLP(57) **CLAIM**

The ornamental design for a vehicle wheel rim, as shown and described.

DESCRIPTION

FIG. 1 is a front perspective view of a vehicle wheel rim showing my new design;

FIG. 2 is a front elevation view thereof;

FIG. 3 is a top plan view thereof, of which the bottom plan view is a mirror image;

FIG. 4 is a side elevation view thereof, of which the opposing side elevation view is a mirror image;

FIG. 5 is a front perspective view of a vehicle wheel rim showing my new design in accordance with an alternate embodiment;

FIG. 6 is a front elevation view thereof;

FIG. 7 is a top plan view thereof, of which the bottom plan view is a mirror image; and,

FIG. 8 is a side elevation view thereof, of which the opposing side elevation view is a mirror image.
